UNITED STATES PATENT OFFICE.

ORANGE O. OZIAS, OF DAYTON, OHIO, ASSIGNOR TO THE COMPUTING SCALE COMPANY, OF OHIO.

DESIGN FOR A FACE-PLATE FOR SCALES.

SPECIFICATION forming part of Design No. 31,927, dated December 5, 1899.

Application filed October 30, 1899. Serial No. 736,331. Term of patent 3¹/2 years.

To all whom it may concern:

Be it known that I, ORANGE O. OZIAS, a citizen of the United States, residing in Dayton, in the county of Montgomery and State of Ohio, have produced a new and original Design for a Face-Plate for Scales, of which the following is a specification, reference being had to the accompanying drawings, forming part thereof, in which like numerals refer 10 to like parts.

In the drawings, Figure 1 represents a front elevation of a face-plate for scales embodying my invention and design, and Fig. 2 is a sectional view thereof on line X X of Fig. 1.

15 The leading or essential feature of my design consists of a circular ring with a series of arms extending toward the center thereof, with indicator-openings between said arms, one edge of said openings being in the arc of 20 a circle.

In said drawings, 10 represents said indicator face-plate for scales formed of the flat relatively wide circular ring 11, having the series of arms 12 projecting toward and uniting at the center thereof. 14, 15, and 16 represent the indicator-openings between said arms 12, and 17 represents the one edge of each of said openings in the arc of a circle. 25

What I claim is—

The design for a face-plate for scales, substantially as shown and described. 30

In witness whereof I have hereunto set my hand this 27th day of September, 1899.

ORANGE O. OZIAS.
